ICE CREAM DIPPER

Estel O. Wheaton, Maumee, Ohio, assignor to Roll Dippers, Inc., Maumee, Ohio, a corporation of Ohio

Application January 18, 1957, Serial No. 44,519

Term of patent 14 years

(Cl. D44—29)

Fig. I

Fig. III

Fig. II

Fig. IV

Fig. I is a side elevational view of an ice cream dipper of my new design;

Fig. II is a top perspective view thereof;

Fig. III is a bottom perspective view thereof; and

Fig. IV is a cross section taken in the line IV—IV of Fig. III.

I claim:

The ornamental design for an ice cream dipper, as shown.
